(57) **CLAIM**

The ornamental design for a electric brake actuator for vehicles, as shown and described.

DESCRIPTION

FIG. 1 is a front view of an electric brake actuator for vehicles showing our new design;

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a front perspective view thereof as seen from the top left side; and,

FIG. 8 is a rear perspective view thereof as seen from the bottom right side.
